J. Pitt.

Cotton Picker Cylinder

Nº 10,578.

Patented Feb. 28, 1854.

UNITED STATES PATENT OFFICE.

JAMES PITTS, OF LANCASTER, MASSACHUSETTS.

COTTON-PICKER CYLINDER.

Specification of Letters Patent No. 10,578, dated February 28, 1854.

To all whom it may concern:

Be it known that I, JAMES PITTS, of Lancaster, in the county of Worcester and State of Massachusetts, have invented a new and 5 useful Improvement in Cotton-Picker Cylinders; and I do hereby declare that the same is fully described and represented in the following specification and the accompanying drawings, figures, letters, and references thereof.

Of the said drawings Figure 1, denotes an end view of that part of a cotton picker, to which the lap cylinders are applied. Fig. 2, is a view of the other end of the same. 15 Fig. 3, is a vertical and central transverse section of it. Fig. 4, is a vertical and longitudinal section of it. Fig. 5, is a side view of one of the cylinders on an enlarged scale.

In the said drawings, A and B denote 20 the two lap forming cylinders against the outer surface of which the loose cotton is thrown, and by which during the revolution of the two cylinders in the directions denoted by the arrows in the drawings, it is 25 formed into a thin sheet or lap.

C, denotes the shrouding or set of lags, and, D, the frame for supporting the cylinders and lags.

The two cylinders are made of cast iron or 30 other proper metal, and are formed with large tubular journals, E, F, E', F', projecting respectively from their two ends. On the two journals, F, F', gears H, I, are placed and made to engage with each other, 35 such journals being made with openings large enough to freely allow a person to pass his hand and arm through them and into the interior of their respective cylinders, in order to enable him to remove while 40 the cylinders may be in rotation or still, any surplus cotton that may have collected within them.

In the use of these cylinders, the tunnel or pipe of an air exhausting wheel or apparatus is to be applied to each of the other 45 journals of the cylinders, so as to cause currents of air to pass through the perforated sides of the cylinders, and into the cylinders and out through the said journals; such currents, as is well known, cause the filaments of the cotton, or fibrous material to plank themselves on the external surfaces of the cylinders. In the manufacture of such cylinders, or cylinder screens, as they are usually termed, as have been in general use be-

fore the date of my invention, they have been commonly made with arms and bars, for supporting a wire or wire gauze covering. Around or on these arms as well as the bars, the cotton filaments become more or less packed, and to such extent as to constantly injuriously affect the operations of the machine. Besides, the wires composing the wire covering, have been of such small diameter or diameters that filaments of cotton or the fibrous material would lap entirely around them and become matted or tied together at their two ends. The length of the staple of cotton varies somewhat, it being generally speaking about one inch and one eighth or one quarter in length. The clogging of the meshes or air passages between the wires, by the embracing of the wires by the cotton in such manner, is a source of great trouble in the operation of the cylinders, and it is to overcome this evil, that I construct my cylinders in the improved manner, in which I shall now proceed to describe. They are made of cast iron and hollow and perforated with holes as seen at a, a, a, &c., the thickness of the metal and the distance between any two holes next adjacent to each other, being made equal to or generally greater than the length of the staple of the cotton or fibrous material to be picked by them. When this is the case, the periphery of the metal intervening between any two orifices next adjacent to each other, being equal to or greater than the length of the fiber, such fiber can in no way so wind around such, as to lap or tie its two ends, in such manner as to fasten it to the metal. Consequently, when a cylinder is so made, it has been found in practice, that the fibers rarely if ever clog the air passages. Besides this, by using the hollow perforated cast metal cylinder, made with hollow journals, we entirely dispense with the support bars and arms, which operate so much to clog the air passages.

What therefore I claim as my invention is as follows, viz:

1. I claim as my improvement in the cotton picker cylindric screen; the constructing the screen so that the periphery of the metal intervening between any two immediately adjacent orifices shall be of a length equal to or greater than that of the staple of cotton or other fibrous material to be picked, in order that the fiber shall not lap around

the said periphery and become connected, attached or tied by its ends as stated.

2. I also claim the improvement of constructing the cylinder screen of a hollow perforated metal cylinder without arms or ribs, and with open hollow cylindric journals at its two ends, as stated, in order that the cotton may be drawn out of one journal by the suction draft and any obstruction re-

moved by a person's hand and arm introduced through the other journal as specified.

In testimony whereof I have hereto set my signature, this twenty-first day of February, A. D. 1853.

JAMES PITTS.
